UNITED STATES PATENT OFFICE.

DANIEL B. WESSON, OF SPRINGFIELD, MASSACHUSETTS.

FRONT SIGHT FOR REVOLVERS.

SPECIFICATION forming part of Letters Patent No. 715,223, dated December 2, 1902.

Application filed May 10, 1902. Serial No. 106,741. (No model.)

To all whom it may concern:

Be it known that I, DANIEL B. WESSON, a citizen of the United States of America, residing at Springfield, in the county of Hampden and State of Massachusetts, have invented 5 new and useful Improvements in Front Sights for Revolvers, of which the following is a specification.

This invention relates to firearms, and particularly to the construction of the front sight therefor, the object of the invention being to provide a vertically-adjustable front sight for firearms which may be easily adjusted up or down to properly sight the arm and which 15 may be locked securely in its adjusted position, all of the parts of the sight being so constructed as to give it a compact appearance with a smooth exterior.

Referring to the drawings in this application, Figure 1 is a side elevation of a sight constructed according to my invention, a portion of the barrel on which it is mounted being shown. Fig. 2 is a sectional plan view of the same on line 2 2, Fig. 1. Fig. 3 is a 25 cross-section on line 3 3, Fig. 1; and Fig. 4 is a perspective view with the side plates of the sight removed. Fig. 5 is a perspective view of the side plate.

For the sake of clearness the parts of the 30 sight have been considerably enlarged.

In carrying out my invention I provide a block *a* as a base for the sight, which may be mounted upon the barrel *b* and secured thereon in any suitable way, or, as shown in Fig. 35 3 of the drawings, it may form an integral part of the barrel. In this block *a* there is located a longitudinally-disposed recess extending from the upper surface thereof through the block and is located substantially 40 midway between the sides and the ends thereof and adapted to receive the blade *c*, which constitutes the "sight." The rear edge of this sight is, as usual in this type, higher than the front edge, and the upper edge thereof is beveled. Near the lower edge thereof a slot *d* is cut therethrough parallel with the axis of the barrel, or substantially so. From one border of the recess which receives the sight the block *a* is cut away and a side plate 45 *e* (shown in Fig. 5) is fitted into this side of the block. The thickness of the blade *c* is somewhat greater than the width of the re-

cess in which it is located, and the side plate *e* is, by means of the screws *f*, clamped against the side of the plate *c* with sufficient force to bind the latter tightly in any adjusted position to which it may be set. In the side plate *e* there is mounted a revoluble disk *g*, which lies in a recess countersunk on the inner surface of the plate, and attached to or forming part of this disk is a smaller disk or head *h*, which projects through the outer surface of the plate, this head being slotted to receive a screw-driver. Mounted upon the edge of the disk *g* there is a crank-pin *i*, parallel with the axis of said disk, which crank-pin enters the slot *d* in the lower portion of the sight. The center of the disk *g* lies substantially over the center of this horizontal slot *d*, and it follows that as this disk *g* is turned to the right or to the left (assuming the parts to be in the position shown in Fig. 3) the crank-pin *i*, bearing against the upper edge of the said slot, will elevate the sight, it being of course understood that the screws *f* have been loosened sufficiently to permit its movement. By reversing the movement of the disk *g* the sight may be depressed.

When the proper adjustment has been made, 8 the screws *f* may be tightened and the sight clamped between one side of the recess in which it is located and said plate *e*.

The heads of the screws *f* are all countersunk substantially flush with the sides of the block *a*, as is also the head *h*, the plate *e* also being let in flush with the side of the block *a*.

The sight thus constructed presents a smooth exterior, to the end that whether mounted upon the muzzle of a pistol or gun-barrel it presents no projecting parts on which anything may catch. It may be readily adjusted and so securely locked in its adjusted position that it will stand quite a blow without being thrown out of adjustment. It 9 is a sight which is particularly well adapted to revolvers, the construction of the breech-end of which but ill adapts them for the use of a rear sight.

Having thus described my invention, what I claim, and desire to secure by Letters Patent of the United States, is—

An adjustable sight for firearms consisting of a base having a recess cut in one side there-

of; a blade constituting the sight proper located in said recess, the thickness of which is greater than the depth of said recess; a side plate and means for securing it to the base against the side of the sight to clamp the latter in the base; an eccentrically-supported revoluble crank-pin mounted in said side plate, there being a horizontal slot in

the said sight in which said pin is located whereby the eccentric rotation of the pin may effect the vertical adjustment of said sight.

DANIEL B. WESSON.
